United States Patent

Des. 234,913
Patented Apr. 15, 1975

234,913

BOTTLE

Fred Ferdinand Morgan, Blonay, Switzerland, assignor to
Societe d'Assistance Technique Pour Produits Nestle
S.A., Lausanne, Switzerland

Filed May 14, 1973, Ser. No. 359,622

Term of patent 14 years

Int. Cl. D9—01

U.S. Cl. D9—163

Fig. 2

Fig. 1

Fig. 3

Fig. 4

FIG. 1 is a side elevational view of a bottle showing my new design, the other three sides being the same in appearance as the side shown;

FIG. 2 is a top plan view thereof;

FIG. 3 is a bottom plan view thereof; and

FIG. 4 is a sectional view taken along lines 4—4 of FIG. 1.

I claim:

The ornamental design for a bottle, as shown and described.
